To whom it may concern:

Be it known that I, George H. Wheary, a citizen of the United States, residing at Racine, in the county of Racine and State of Wisconsin, have invented a new, original, and ornamental Design for a Hand Luggage Case, of which the following is a specification, reference being had to the accompanying drawing, forming a part thereof.

The figure is a perspective view of a hand lug-

The characteristic features of my design reside in the metal moulding strips which encircle the case, and the corner caps, each cap having a projection which extends to the adjacent strip.

I claim:

The ornamental design for a hand luggage case, as shown and described.
